COMBINED UMBRELLA AND SHEATH PACKAGE

Fritz Bremshey, Solingen-Ohligs, Germany, assignor to
Telesco Brophey Limited, East Montreal, Quebec,
Canada

Filed Dec. 2, 1968, Ser. No. 14,739

Term of patent 14 years

Int. Cl. D9—99

U.S. Cl. D9—193

FIG. 5

FIG. 4

FIG. 1

FIG. 2

FIG. 3

FIG. 6

FIG. 1 is a plan view taken from a front face of the combined umbrella-and-sheath package according to my design;

FIG. 2 is a side view taken from one side of the umbrella and sheath;

FIG. 3 is a plan view taken from the rear face of the umbrella and sheath;

FIG. 4 is a side view taken from the other side of the umbrella and sheath;

FIG. 5 is an end view taken from the handle end of the umbrella and sheath;

FIG. 6 is an end view taken from the other end of the umbrella and sheath.

I claim:

The ornamental design for a combined umbrella and sheath package, as shown.
